Hezekiah Camps.

Letters Patent.

The Schedule referred to in these Letters Patent and making part of the same, containing a description in the words of the said Hezekiah Camps, himself of his improvement in the Printing Press.

To all to whom these presents shall come: Be it known that Hezekiah Camps of Boston, in the said State of Mass., have invented a new and useful improvement in the Printing Press, called Camps' Improved Press; and that the following is a full and exact description thereof. First: consist of a rectangular frame A of any size desired, and of sufficient height to admit the convenience of the operator, and support it by four posts. The sides of the frame to be ploughed or formed on the top frame and toad, to admit of the ends of the bed B, to be placed thereon. In these grooves are to be inserted metal bearings or hollows in which the ends of the bed B are to run, but consist not in movable bed B, similar to that of the common printing press, and moved in the common manner, by a crank pulley and steppon. An additional pulley may be used, and the crank placed to the left hand of the operator in order to accommodate his habitual motion. In this case the two pulleys are to be connected by additional steps. The bed may be made of wood, wrought or cast iron, and consist of two side plates C, to be fastened to the frame A about one fourth of the distance of the length of the frame from the right hand end of said frame one on each side of sufficient size to contain the journals of the press roller D, and the blocks E, which confine the press roller E, down to printing point and thickings F, which raise the roller and hold it up whilst the form press is back after the impression is taken. The press roller E may be made of wood or metal size not material and covered with cloth. The journals pass through the side plates C, playing upon them so as to admit of an inch or more and resting upon the blocks F, a metal block E, is let into each side plate C, the upper end containing a slot to admit the journal of the press roller with a sliding box and adjusting screw, the lower

end of the hooks being formed in an angle of about 75 degrees and turned towards the left end of the bed with a circular notch on the inside corner of the angle to fit a pin or bolt which is to be fastened into the frame. . which bolts form the journals of the rollers $\mathfrak{g}$, immediately under the projectors $\mathfrak{d}$, and on which the bed $\mathfrak{b}$, turns. The hooks $\mathfrak{e}$ connect the journals of the rollers $\mathfrak{g}$, with the journals of the press roller $\mathfrak{h}$, and are adjusted to confine the press roller during the operation of printing to the proper point to make the impression and are fastened at the lower ends by means of pins projecting out of the sides of the bed $\mathfrak{b}$ near the left hand end of the bed. This operation the bed is caused forward till the impression is fully made. While the hooks near the lower end and confine the roller from the roller journals, the rollers and the springs $\mathfrak{f}$ at the same instant raise the roller $\mathfrak{g}$ about a fourth of an inch and sustain it while the bed and frame are running back. Near the other end of the bed $\mathfrak{b}$ are two circular pieces, which as the bed returns strike the hooks on the opposite side and fasten or lock them upon the bed to stop the hooks from the opposite side and fasten or lock them upon the bed to stop them, thereby bringing the press roller down to printing point. A flat construction upright piece $\mathfrak{i}$, fastened to the right hand end of the frame $\mathfrak{b}$ to support the upper end of the platform $\mathfrak{c}$, which is made of wood and placed at an angle of 45° to the frame $\mathfrak{b}$, the lower end resting upon the upper end of the side plates $\mathfrak{e}$. Said platform must be of sufficient size to accommodate the length and width of the sheet to be printed. That make a flexible tympan of fine leather, bison leather or some other suitable material as large as the sheet to be printed requires. The lower end of which is to be fastened to the right hand end of the bed $\mathfrak{b}$. The other end of the tympan is brought under the projectors $\mathfrak{d}$, and laid upon the platform $\mathfrak{c}$. At the upper end of the tympan attach clamps $\mathfrak{k}$, to hold the upper end of the sheet. They are kept together by a spring catch and are opened by a point attached to the platform passing in between them and receding off the catch, out of the tympan in contact. Another spring is placed between the clamps $\mathfrak{k}$ to draw them open when released from the spring catch. Near the lower end of the tympan are other clamps to hold the other end of the sheet. They are kept together by a spring catch at each end and project about one half inch beyond the sides of the tympan, and will be of a edged formed piece of iron.

are attached to the platform) to pass in between them a wire suspending
catches and for catching open another coming in contact with these
pieces. The upper ends of the pieces A & B support a shaft C, containing
two grooved pulleys, so far apart as the tympan is wide, and exactly
opposite the upper corners of the tympan. To these corners of said
tympan are the ends of cords attached the other ends of said cords are
fastened to the pulleys - These cords being wound upon these pulleys so
as that another pulley is attached to one of the outer ends of the same shaft
with a weight suspended from it by means of another cord (so that when
the tympan is carried down in the operation of printing the weight
is drawn up, and when the tympan is permitted to return, the weight
comes down (and being sufficiently heavy) carries the tympan
together with the printed sheet back upon the platform to its original
position. The rollers D, are suspended over the lower end of the platform
by means of a wire shaft attached to the journals of the press roller,
the object of these rollers is to shut the lower clamps. Damping may be
performed in the usual way or by one or more distributing rollers in
the end of the frame on which the bed moves, turned by a strap around
a pulley attached to one of the distributing, and around another pulley
attached to the main shaft, the inking roller being confined in a
stock is placed upon the distributor, and the moving of the bed puts
in motion the rollers by which means the distribution of the ink
is produced. Damping may be performed by a supplying roller with
distributors placed in such a position as to ink the type by the motion
of the bed (as represented in the drawing) thus obviating the
necessity of a person to ink. Mode of Operation - since the form
is in the bed in the usual manner, damping may be performed in the
usual manner, or as above described or represented in the draw-
ing. Place the sheet upon the tympan in the usual manner which is
confined at each end and by shutting the clamps. Then by turning
the crank the form is forced under the press roller, the tympan
and paper being carried under it, the same time the impression is
made and as soon as this is performed the press roller rises up, and

The crank being turned back the form is raised, and the type is arranged and sheet are at the same time carried back upon the platforms and the clamps fly open leaving the sheet ready to be taken off. What I claim as my own invention and not previously known in the above described machine, is the principle of throwing the type roller in contact of gear by means of the hooks or otherwise and of the manner of raising the type roller and keeping it suspended while the form is back, thereby preventing the impression from being injured—also a flexible typestan off opening clamps, and all other necessary apparatus there to belonging as above described.
